CAB FOR AMUSEMENT RIDE

Ralph A. Simpkins, deceased, late of Columbus, Ohio, by Margaret R. Simpkins, administratrix, 3075 Right-
mire, Columbus, Ohio

Filed Dec. 21, 1959, Ser. No. 58,725

Term of patent 14 years

(Cl. D34—5)

FIG. 1

Fig. 1 is a front elevational view of a cab for amusement ride, showing the new design;
Fig. 2 is a side elevational view thereof; and
Fig. 3 is a top plan view thereof.

What is claimed is:
The ornamental design for a cab for amusement ride,
substantially as shown.
